(57) **CLAIM**

We claim the ornamental design for a dripper valve for drip coffee machine, as shown and described.

DESCRIPTION

FIG. 1 is a front perspective view of a dripper valve for drip coffee machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view showing a state of use thereof.

The broken lines in FIG. 9 are for environment purpose only and form no part of the claimed design. The broken lines shown in the drawings illustrate portions of the dripper valve for drip coffee machine that form no part of the claimed design.

1 Claim, 9 Drawing Sheets
